FOLDING DISH-DRYING RACK

George Einhorn, Forest Hills, N. Y.

Application September 3, 1947, Serial No. 771,971

2 Claims. (Cl. 211—41)

1

This invention relates to a collapsible or folding rack for holding dishes, eating utensils and the like, and has as its general object, the provision of a collapsible rack which may be rapidly set up to operative condition and retained in operative condition without accidental collapse, and which may be collapsed into small compass after use, in order to conserve storage space until its use is again required.

A further object of the invention is the provision of a collapsible rack of the character indicated which may be easily and inexpensively fabricated at low cost from round wire stock or other suitable material, and which comprises a minimum number of parts assembled in a simple manner to produce a unit having great strength and durability.

The foregoing objects, as well as additional objects and advantages of the invention will be readily apparent in the course of the following detailed description taken in connection with the accompanying drawings which illustrate a preferred embodiment of the invention and wherein:

Fig. 1 is a top plan view of a rack embodying the features of the invention, the rack being shown in collapsed, inoperative condition.

Fig. 2 is a similar view showing the rack in open, operative condition for the reception of dishes, eating utensils, and the like.

Fig. 3 is a front elevation of the rack of Fig. 2, showing the dish-supporting elements in inclined operative position.

Fig. 4 is a sectional view taken along line 4—4 of Fig. 2.

Fig. 5 is a fragmentary detail view illustrating the operation of the push-bar control for raising the dish-supporting elements from substantially coplanar inoperative alignment to inclined, substantially parallel operative alignment, the intermediate position of the elements being shown in broken outline.

Fig. 6 is a fragmentary detail view similar to Fig. 5, but illustrating the final operative position of the dish-supporting elements.

Fig. 7 is a sectional view taken along line 7—7 of Fig. 2, illustrating a preferred form of jackknife or over-center pivot arrangement for yieldingly retaining the side wall in operative condition.

Fig. 8 is a similar view showing the side wall partially turned inwardly in the operation of collapsing the rack.

Fig. 9 is a plan view of a preferred form of dish-supporting element.

2

Fig. 10 is an elevational view of the dish-supporting element shown in Fig. 9.

Fig. 11 is a fragmentary end view, as seen in the direction of the arrows on lines 11—11 of Fig. 2.

The rack is preferably formed from round wire stock which may have a protective coating of rubber or synthetic resin or rust-resistant metal. The use of wire is desirable to provide open network construction in order to allow wet dishes and eating utensils to drain properly to provide a sufficient circulation of air through the rack for rapid drying of the articles held thereupon.

The rack is provided with a base 10 defined by a continuous rectangular frame of wire having the sides 11 and ends 12. Said base 10 is crossed by longitudinal rods 13 and transverse rods 14. The transverse rods 14 do not extend for the complete width of the rack in order to provide a section of the rack for mounting the dish-supporting elements 15.

Said elements 15 are preferably shaped with a main arcuate portion 15a, an integral crank portion 15b at one end of said arcuate portion and a mounting lug 15c at the opposite end of said arcuate portion. Crank portion 15b is askew with respect to main portion 15a, as clearly indicated in Figs. 5, 6 and 10 for a purpose to be fully described hereinafter.

A plurality of elements 15 are pivotally supported between an adjacent pair of longitudinal rods 13a in any suitable manner. A convenient arrangement involves the use of a pair of supporting members 16 having depressions or nodes 16a spaced therealong, each being secured below a respective longitudinal rod 13a, as by means of soldering or spot-welding, thereby allowing each element 15 to be pivotally mounted between an opposed pair of nodes or depressions 16a, as clearly shown in Figs. 4, 5 and 6. Each element 15 is preferably mounted with the crank portion 15b positioned outwardly, and the lug portion 15c positioned inwardly to make said crank portion easily accessible for attachment to and manipulation by a push-bar 17.

A pair of mounting plates 18 is suitably positioned and secured to ends 12 of base 10 to serve as legs for the tray and also to serve as guides for slidably reciprocating push-bar 17 by means of slots 18a formed in each of said plates. Push-bar 17 is further provided with a plurality of spaced apertures for the reception of crank portions 15b of elements 15. As has been previously pointed out, crank portion 15b of each element 15 is askew with respect to main arcu-

ate portion 15a to allow pivotal rotation of said elements from the substantially coplanar inoperative alignment of Figs. 1 and 5 to the inclined, substantially parallel operative alignment of Figs. 2 and 6, by the manual manipulation of push-bar 17 in respective opposite directions. More specifically, elements 15 are rotated to inclined operative position by moving push-bar 17 to the right and are rotated to substantially coplanar inoperative position by moving said push-bar to the left, as shown by the arrows in Fig. 3.

Another feature of the invention resides in the construction and arrangement of collapsible side wall 20, which may be formed with a top 21 and integral sides 22. A mounting rod 13a is secured as by soldering or spot-welding adjacent the side 11 and on the bottom of base 10. Said mounting rod 13a is substantially parallel to the longitudinal supporting rods 13, but is secured on the opposite side or bottom of the base 10. The sides 22 of side wall 20 are each formed with a terminal loop 22a which may be passed over mounting rod 13a for pivotal connection of said side wall about said mounting rod. A lower longitudinal rod 23 and intermediate transverse struts 24 may be employed to reinforce the side wall 20. The terminal struts 24a are preferably extended downwardly to form a pair of depending legs 25 interconnected by a longitudinal portion 25a. Legs 25 are preferably turned inwardly, as clearly shown at 26, in Figs. 7 and 8, to provide a jackknife or over-center arrangement for releasably engaging side wall 20 against side 11 of base 10, as said side wall is pivoted to its extended operative condition.

The rack is also provided with a pair of end walls 30, each end wall being pivotally engaged with a respective end 12 of base 10. Each end wall 30 may be defined by a top 31 and sides 32 integral therewith. The sides 32 may be formed with a terminal loop 32a which may be passed over a respective end 12 of base 10 to provide pivotal connection therewith, the outward movement of each of end walls 30 being limited by means of a longitudinal U-shaped stop member 33 fixed to the end 12 of base 10. The bottom of sides 32 of each end wall 30 is preferably inwardly curved adjacent loop portion 32a as shown at 34 in Fig. 3, to allow said end walls to be flat against inwardly folded side wall 20 in the collapsed inoperative condition of the rack.

Since certain modifications may be made in the rack of the invention without departing from the scope thereof, it is intended that all matter contained in the foregoing description and shown in the accompanying drawings be interpreted merely as illustrative and not in a limiting sense.

Having thus described my invention, what I claim as new and desire to secure by Letters Patent, is:

1. A collapsible rack for dishes, eating utensils and the like, said rack comprising a base defined by a rectangular wire frame, said base having longitudinal rods extending thereacross and connected to the frame at its ends, a plurality of dish-supporting elements extending between and pivotally secured to an adjacent pair of longitudinal rods, each of said elements including a crank portion, a pair of mounting plates secured to said base, a reciprocable push-bar carried by said plates, said push-bar having a plurality of spaced apertures receiving said crank portions, a side wall pivoted to said base, said side wall being formed with a pair of integral depending legs, said legs being engageable against said base for releasably retaining said side wall in raised operative position, a pair of end walls pivoted to said base, and a U-shaped stop member fixed to said base at each end thereof for limiting the outward movement of each of said end walls.
2. A collapsible rack in accordance with claim 1, wherein each of said dish-supporting elements is provided with a main arcuate portion, said crank portion being in offset relation with respect to said main arcuate portion, whereby to allow rotation of said elements from an inoperative position substantially coplanar with said base to an operative inclined position of substantially parallel alignment.

GEORGE EINHORN.
